UNITED STATES PATENT OFFICE

2,545,418

IMMERSION HEATER FOR LIQUIDS

Jerry C. Wiesner, Granville, and James R. Carey,
Albany, N. Y.

Application January 14, 1949, Serial No. 70,932

5 Claims. (Cl. 219—40)

1

This invention relates to new and useful improvements and structural refinements in immersion-type heaters for liquids, either liquid in closed containers such as hot water tanks, pressure cookers, cooling jackets or internal combustion engines, etc., or in open containers such as double boilers, percolators, etc., and in particular the invention concerns itself with that type of an immersion heater wherein two or more electrodes are immersed in and are in electrical contact with the liquid to be heated, so that the liquid itself actually becomes a part of the electrical circuit and by offering a resistance thereto, the desired heating effect is created.

Some of the objects of this invention are to eliminate the breakage of electrodes, to substantially minimize electrolytic activity such as would produce undesirable coating or deposit of foreign matter on the electrodes, to substantially minimize if not completely eliminate disintegration of the electrodes by electrolytic action, and to assure proper circulation of the liquid around the electrodes so as to substantially increase the operating efficiency of the heater as compared to heaters of conventional type.

Additional objects of the invention are to eliminate arcing between the electrodes, to prevent undesired discoloration of the liquid being heated, to prevent any taste from being imparted to the liquid by the heating action, and to render the heater fully automatic in operation and capable of maintaining the liquid at a predetermined degree of temperature.

These objects are achieved by the provision of the instant heater, wherein the electrodes are firmly and securely supported in spaced relation so as to eliminate the possibility of breakage while assuring proper circulation of the liquid therebetween, wherein the electrodes are constructed from a particular type of material which is non-corrosive and adapted to discourage or repel accumulation of foreign matter thereon, and wherein adjustable, thermostatically actuated means are provided for controlling the flow of current through the electrodes so as to maintain the liquid at a predetermined degree of temperature.

Some of the advantages of the invention lie in its simplicity of construction, in its adaptability to expeditious disassembly for purposes of inspection or repair, and in its adaptability to economical manufacture.

With the above more important objects and features in view, and such other objects and features as may become apparent as this specifica-

2

tion proceeds, the invention consists essentially of the arrangement and construction of parts as illustrated in the accompanying drawings, in which:

5 Figure 1 is a side elevational view of the invention;

Figure 2 is a longitudinal cross-sectional view thereof, taken substantially in the plane of the line 2—2 in Figure 1;

10 Figure 3 is an end view, taken in a direction of the arrow 3 in Figure 2;

Figure 4 is a cross-sectional view, taken substantially in the plane of the line 4—4 in Figure 1;

15 Figure 5 is a cross-sectional view taken substantially in the plane of the line 5—5 in Figure 2;

Figure 6 is a cross-sectional view, taken substantially in the plane of the line 6—6 in Figure 2; and

20 Figure 7 is a fragmentary perspective view of a control rod used in the invention.

Like characters of reference are employed to designate like parts in the specification and throughout the several views.

25 Referring now to the accompanying drawings in detail, the invention consists of an immersion-type liquid heater designated generally by the reference character 10, the same embodying in its construction a screw-threaded mounting head

30 12 including a polygonal wrench-receiving portion 14, one end surface of the head 12 being formed with a circular recess 16 to receive a disk-shaped electrode holder 18 formed from suitable insulating material.

35 A further electrode holder 20 of similar construction is disposed in spaced, axially aligned position relative to the holder 18, and a tubular stem 22 extends axially through the holders 18, 20, as is best shown in Figure 2.

40 A cylindrical housing 24 is associated with the holder 20 by having this holder positioned adjacent one end thereof as shown in Figure 2, the housing 24 being formed with a screw-threaded boss 26 to receive a screw-threaded end portion of the stem 22, as will be clearly apparent.

45 The remaining end portion of the stem 22 is formed with an annular shoulder 28 embedded in the head 12, this end portion of the stem extending sufficiently into the head so as to project into a cylindrical bore 30 with which the head is provided. This end portion of the stem 22 is also screw-threaded to receive a securing nut 32, and suitable packing 34 may, of course, be used for preventing leakage of liquid into the bore 30 of

the head, as will be clearly apparent (see Figure 2).

A set of electrodes 36-50, inclusively, are securely mounted between the holders 18, 20, this being achieved by providing the holders with suitable recesses as exemplified at 52, to receive end portions of the electrodes. It will be observed that by tightening the nut 32, the holder 20 together with the housing 24 will be drawn toward the head 12 and, as a result, the electrodes will be firmly secured in position between the holders thereof. The electrodes 36-50 preferably assume the form of flat straps disposed in juxtaposed relation and arranged in a substantially cylindrical formation so that a longitudinal edge of one strap is laterally staggered from the corresponding edge of the next adjacent strap, as is best shown in Figure 4. When the invention is installed, the head 12 should be so adjusted that the electrode straps are disposed in vertical planes, thus assuring proper circulation of liquid therebetween by forces of convection.

The electrode straps are preferably formed from silver plated copper alloy or beryllium copper of the following composition:

	Per cent
Beryllium	2.5 to 3.0
Nickel	0.6 to 0.8
Iron	1.2 to 1.3
Copper	94.9 to 95.7

A switch assembly 54 is provided in the bore 30 of the head 12, this switch assembly embodying a hollow, substantially cylindrical housing 56 which is positioned in the bore 30 and is formed with an annular groove 58 to accommodate a set screw 60 with which the head 12 is provided, whereby the switch assembly is retained in position in the head.

An adapter 62 is secured to the switch housing 56 by a plurality of screws 64 and is disposed exteriorly of the head 12, being formed with a pair of sockets 66, 68 to receive the usual prongs of a conventional attachment plug (not shown) whereby a supply of electric current is delivered to the heater.

One of these sockets, namely, the socket 68, is connected by suitable conductors 70 extending in the head 12 to the electrodes 36, 40, 44, 45 and 48, while the remaining electrodes 38, 42, 43, 46 and 50 are similarly connected by additional conductors 72 to a stationary contact member 74 provided in the housing 56 of the switch 54. A swingable contact arm 76 is pivotally mounted in the switch housing as at 78 and is separably engageable with the contact member 74, the arm 76 being, in turn, electrically connected to the remaining socket 66 by a conductor 80.

A suitable tension spring 82 is anchored at one end to the adapter 62 as at 84 while the remaining end of the spring is anchored to the arm 76, whereby the arm is normally maintained out of contact with the member 74, thus normally maintaining the switch assembly 54 in its open position.

A longitudinally shiftable switch control rod 86 is slidably disposed in the aforementioned stem 22, one end portion of this rod extending into the aforementioned housing 24 and being suitably secured to a helical, expansible thermostat 88, the free end of which, in turn, is secured to the housing 24. The thermostat 88 is of the conventional by-metallic construction, as indicated in Figure 2.

The rod 86 extends into the switch housing 56

and is cross sectionally reduced as indicated at 90 so as to provide sufficient clearance for an intermediate portion of the aforementioned switch arm 76. The end portion of the rod 86 disposed in the switch assembly 54 terminates in a split tubular extremity 92 which is screw-threaded to receive an adjusting screw 94, the shank of this screw being engageable with the arm 76 while the head portion of the screw is disposed in a counterbore 96 provided in the adapter 62, whereby the screw is externally accessible for purposes of adjustment.

Having thus described the construction of the invention, its method of operation will now be explained.

Primarily, it is to be observed that the conductors 70, 72 of opposite polarities are connected alternately to the electrodes 36-50, that is to say, regardless of whether direct or alternating current is used, the polarity of one electrode is always different from that of the next adjacent electrode, so that a difference of potential is established between the immediately adjacent electrodes in the set. It should, of course, be understood that when the heater is installed, the several electrodes are in electrical contact with the liquid to be heated so that the liquid actually becomes a part of the electrical circuit resulting from the difference of potential between the next adjacent electrodes and the liquid offers sufficient resistance to the passage of electricity therethrough to create the desired heating effect.

The difference of potential between the electrodes is present when the switch arm 76 is in engagement with the switch member 74, and when the temperature of the liquid ultimately reaches a predetermined point, the thermostat 88 will slide the rod 86 in the direction of the arrow 98 (see Figure 2) so that the arm 76 will become separated from the switch member 74 by the resiliency of the tension spring 82 which tends to draw the arm 76 against the shank end of the adjusting screw 94. Needless to say, by simply rotating the screw 94 in one direction or the other, the temperature at which the switch assembly 54 is opened may be varied, as desired. In any event, opening of the switch 54 will interrupt the supply of current to the electrodes, so that no heating effect will be obtained until the temperature of the liquid cools sufficiently to contract the thermostat 88 and again close the switch 54 by the engagement of the shank end of the screw 94 with the switch arm 76.

The screw-threaded and slotted end portion 92 of the control rod 86 may be sectionally distorted by crimping, or the like, so that the screw-threaded bore 100 of this rod portion is not of a true cylindrical form, whereby the coefficient of friction of the screw 94 in the bore 100 will be substantially increased and undesired rotation of the screw, such as would disturb its predetermined adjustment, will be prevented.

It is believed that the advantages and use of the invention will be clearly apparent from the foregoing disclosure and, accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. In an immersion type liquid heater, the combination of a mounting head, a set of flat electrode straps disposed in juxtaposed relation and secured at one end thereof to said head, an insulating holder provided on the remaining end portions of said straps, a tubular stem disposed between said straps and securing said holder to said head, said straps being adapted for immersion in and electrical contact with the liquid to be heated, and current conductors of opposite polarities extending into said head and each connected to alternate straps of said set whereby a difference of potential may be established between the immediately adjacent straps of said set, a switch connected to one of said conductors for breaking the circuit and positioned in said head, a housing secured to said stem having a coiled bimetal thermostat therein, a rod in said stem fixed to one end of said thermostat and adapted to open said switch at a predetermined temperature.

2. The device as defined in claim 1, wherein said straps are of different widths and are mounted in a substantially cylindrical formation whereby a longitudinal edge of one strap is laterally staggered from the corresponding edge of the next adjacent strap.

3. In an immersion type liquid heater, the combination of a mounting head, a set of elongated electrodes disposed in juxtaposed relation and secured at one end thereof to said head, a housing provided at the remaining ends of said electrodes, a tubular stem positioned between said electrodes and securing said housing to said head, a switch mounted in said head, conductors extending into said head and connected to said electrodes through the medium of said switch, an expansible coil thermostat in said housing, and a longitudinally shiftable control rod positioned in said stem and operatively connecting said thermostat to said switch.

4. The device as defined in claim 3, together with an externally adjustable screw provided on said rod in said head, said switch including a pivoted contact arm, and said screw being operatively engageable with said arm, and resilient means for normally urging said switch to open position.

5. A liquid heater comprising: a mounting head having an insulating holder mounted therein, a tubular stem secured to said mounting head at one end and having a housing fixed to its other end, a plurality of electrode straps positioned with their upper ends in said insulating holder and their lower ends in a second insulating holder mounted on said housing, conductors of opposite polarities extending into said head, each of said conductors connected to a plurality of alternate straps for providing a difference of potential between the straps, a switch interposed in one of said conductors, an extensible thermostatic coil in said housing having a rod attached to one end thereof, said rod being concentric with said tubular stem and having its upper end cooperable with said switch and adapted to break the circuit through said conductors at a predetermined temperature.
